(57) **CLAIM**

The ornamental design for LED light distribution lens, as shown and described.

DESCRIPTION

FIG. 1 is a perspective view of an LED light distribution lens taken from the top and front thereof, showing my new design;

FIG. 2 is a top plan view thereof;

FIG. 3 is a front elevational view thereof, the rear elevational view being identical to the front elevational view;

FIG. 4 is a bottom plan view thereof;

FIG. 5 is a right side elevational view thereof, the left side elevational view being identical to the right side elevational view;

FIG. 6 is a cross-sectional view thereof taken along the line VI—VI in FIG. 3; and,

FIG. 7 is an illustrative perspective view showing the lens in use, in which portions shown in broken lines form no part of the claimed design.
